UNITED STATES PATENT OFFICE.

GEORGE W. HOWES, OF DOWAGIAC, MICHIGAN, ASSIGNOR TO THE BECKWITH COMPANY, OF DOWAGIAC, MICHIGAN.

FURNACE.

1,369,434.

Specification of Letters Patent. Patented Feb. 22, 1921.

Original application filed June 11, 1919, Serial No. 303,336. Divided and this application filed September 25, 1919. Serial No. 326,369.

To all whom it may concern:

Be it known that I, GEORGE W. HOWES, a citizen of the United States, residing at Dowagiac, county of Cass, State of Michigan, have invented certain new and useful improvements in Furnaces, of which the following is a specification.

This invention relates to improvements in furnaces.

10 The main objects of this invention are to provide in a furnace an improved casing structure in which the parts are simple and economical to produce and may be assembled by an unskilled workman.

15 Further objects, and objects relating to structural details will definitely appear from the detailed description to follow.

I accomplish the objects of my invention by the devices and means described in the 20 following specification. The invention is clearly defined and pointed out in the claims.

25 A structure which is a preferred embodiment of my invention is clearly illustrated in the accompanying drawing forming a part of this specification, in which:

30 Figure I is a side perspective view of a structure embodying the features of my invention, the top of the outer casing being omitted and a portion of the outer casing being broken away.

Fig. II is a detail side perspective view of the furnace body and front plate.

35 Fig. III is a detail plan view showing details of the front wall and the relation of 35 the casing thereto.

Fig. IV is a detail horizontal section on a line corresponding to line 4—4 of Fig. I.

40 Fig. V is a horizontal section on a line corresponding to line 5—5 of Fig. I, the furnace body front plate being omitted.

In the drawings similar reference characters refer to similar parts throughout the several views and the sectional views are taken looking in the direction of the little 45 arrows at the ends of the section lines.

Referring to the drawing, the furnace body in the structure illustrated is formed of sections 1, 2, 3 and 4. The base 5 is designed to receive the section 1 and constitutes the bottom of the ash pit. The outer casing base ring 6 is connected to the base 5 by the bars 7. The section 1 has a passage 8 while the upper section 4 has a fuel pas-

sage 9. The radiator 10 is mounted upon the section 4.

55 The parts are connected by means of bolts 11 and the radiator section is made adjustable as described in detail in my application for Letters Patent filed June 11, 1919, Serial No. 303,336, of which this application is 60 a division. I provide a front plate 12 having forwardly projecting side flanges 13 to which the outer casing 14 is secured by means of the bolt 15. The front plate is secured to the ash pit and fire pot passages by 65 means of the bolts 16 arranged through lugs 17 provided on these passages.

The inner casing 18 is double walled in the structure illustrated, its lower edge being mounted on the ring 19, carried by the 70 uprights 20 on the base bars 7. The inner casing members have lapping flanges 21 which overlap the flanges 13 and are supported by the eye bolts 22 engaged on the inner ends of the bolts 16 and which secure 75 the front plate to the body, bolts 17 being provided with nuts 23 on the inner sides of the lugs and nuts 24 on the inner sides of the eye bolts to retain the same.

The furnace illustrated is one of the one 80 register type, the top of the outer casing not being illustrated as such top forms no part of this invention. It is sufficient to say that the air circulates downward through the inner casing and up through the inner cas- 85 ing around the body and radiator.

I have shown in the accompanying drawings the inner and outer casings as formed of one piece, but in practice they may be of two or more strips having joint rings be- 90 tween them.

My improved furnace is designed so that it may be shipped knock-down and set up or assembled in the place of installation by an unskilled workman. This is especially feasible where my improvements are embodied in one register furnaces as illustrated.

Having thus described my invention, what I claim as new and desire to secure by Letters Patent is:

1. The combination with a furnace body, 100 of a front plate mounted thereon and having forwardly projecting side flanges, an outer casing attached to the edges of said flanges, spaced inner casing members having 105 forwardly projecting overlapping flanges

lapped upon the flanges of said front plate, and means for drawing said overlapping casing member flanges against flanges of said front plate.

5. The combination with a furnace body, of a front plate mounted thereon, an inner casing member having forwardly projecting flanges overlapping the flanges on said front plate, and means at the rear of said front plate for drawing said casing flanges against the front plate.

10. The combination with a furnace body provided with front plate attaching lugs, of a front plate having forwardly projecting

side flanges, an inner casing member having 15 forwardly projecting flanges lapped upon the flanges of said front plate, securing bolts for said front plate disposed through said attaching lugs, and eye bolts engaging with said securing bolts and disposed through the 20 flanges of said inner casing member, whereby said inner casing is supported and its flanges are drawn against said front plate flanges.

In witness whereof I have hereunto set 25 my hand and seal.

GEORGE W. HOWES. [L.S.]
